SAFETY PIN

Charles Milton Clark, Clearwater, Fla.

Application September 20, 1951, Serial No. 247,411

1 Claim. (Cl. 24—156)

1

The present invention relates to improvements in safety pins.

Heretofore the standard type safety pin has been made with a metal guard which receives the point end of the pin. This metal guard of the prior art includes a beak portion or nose against which the pointed end of the pin presses when the pin is closed. These metal guards, particularly at the nose or beak portion, are subject to becoming bent and distorted, so that the pin point will often become displaced and the pin point exposed resulting in possible injury to the wearer of the pinned garment.

It is an object of the present invention to provide a plastic pin guard, which will not bend or become distorted, whereby the pin will stay closed at all times until manually released.

Another object is to provide a pin with a safety guard having a side guard entrance and exit opening and wherein the pin is resiliently biased laterally of the guard and in a direction toward the opening, to thereby always keep the point of the pin within the confines of the guard.

Another object is to provide lateral resilient yieldability of the guard on the fixed end of the pin structure by the addition of an auxiliary spring, thereby facilitating the opening and closing of the pin.

Still another object is to provide a pin guard having a double locking effect.

Yet another object is to provide a pin with a safety guard which is more efficient in use, more durable and economical than the guards of prior pins of this type.

The above and other objects and advantages of the invention will appear more fully hereinafter from a consideration of the detailed description which follows, taken together with the accompanying drawings wherein one embodiment thereof is illustrated. It is to be understood, however, that the drawing is for the purpose of illustration only and is not intended to limit the scope of the invention. To determine the scope of the present invention, reference should be had to the appended claim.

In the drawing wherein like reference characters refer to like parts throughout the several views:

Figure 1 is an enlarged perspective view of the present invention pin in closed position.

Figure 2 is a side longitudinal cross section view of the novel pin guard on the section line 2—2 showing the pin structure combined therewith in side elevation.

Figure 3 is a side transverse cross section view

5 of the pin guard showing the pin structure combined therewith in front elevation.

Figure 4 is a bottom plan view of the novel pin guard with a transverse cross section view of the pin structure on the section line 4—4 of Figure 1.

10 Referring in detail to the drawings there is shown a pin combination A comprising a guard 10, a U-shaped pin structure having a leg 11 and a leg 12 and a loop holding base 13. The leg 11 of the pin structure is free at its upper end and is formed with the usual pin point 14, see Figure 2, at this free end, while the end 15 of the leg 12 is curved and embedded in the plastic material at one end of the guard 10. Also, the leg 12 intermediate the base 13 and the end 15 is formed into a coiled spring 16 to provide lateral yieldable movement of the guard 10 on the leg 12, to thereby aid in the pinning action prior to locking the pin in the guard and to always bias the pointed end of the leg 11 to a position under the guard.

15 The guard 10 is a rectangular body closed at the top 17 and preferably rounded for engagement by a user's finger to rock the head or guard 10 on leg 12 and is formed with a rectangular opening 18 at the bottom and one side wall 23. The opening is divided by a partition 19 inset or countersunk within the body substantially parallel to the side wall, see Figures 3 and 4. The partition 19 provides for a lateral channel or side opening 20 defined by the downwardly sloping end wall 21 of partition 19 spaced from the interior face of the end wall 22 of the guard opening 18. This channel 20 serves as a side entrance and exit for the laterally spring biased pin pointed free end of the leg 11 of the pin structure. Thus the partition 19 is within the confines of the top wall 17, the side wall 23 and the end walls of the guard between which the partition extends, so that the pointed end of the leg 11 is always biased inwardly under the top of the guard whether the pin is in actual use or not. With the pin point unexposed under the top wall the point is never out of the confines of the guard.

20 45 The rectangular opening 18 is bounded by an interior face of side wall 23, see Figure 4. The wall 23 is formed with a projection, such as a ratchet tooth 24, which slants upward away from the side opening 20 into an abutment surface at substantially right angles to the side wall 23. This surface serves as a stop to hold the free end 14 of the leg 11 seated and latched inside the guard 10, until manually released by pushing the end 14 toward the partition 19 and thence to-

ward the lateral exit channel 20. As shown in Figure 4, the exterior face 25 of the partition 19 is countersunk below the edge 26 of the guard 10 on the same side with the channel 20 and serves to indicate to the user which direction the leg 11 is to be pushed to release its end 14 from behind the abutment surface of teeth 24. Also, even after the pin end 14 has been released from the tooth 24, it is still necessary to push outward laterally at the channel 20 to clear the pin point 14 from the confines of the guard 10. This feature provides additional safety as the pin point is always confined within the guard except when manually forced laterally outward from the exit channel 20. The partition 19 drops down enough to be seen below outside wall 23. When the pin is in cloth this will show the opening 20 where free end 14 enters.

When using the present novel pin and assuming the pin point 14 is free of the guard 10, the point is inserted into the folds of the fabric to be fastened. Then the index finger may be placed upon the rounded exterior top surface of the guard 10 and the thumb used to manipulate and direct the leg 11 and pin point 14 into the channel 20 and forward between the partition and adjacent interior face of the side wall within the opening 18 over the tooth 24 and into resiliently yieldable engagement with the abutment surface of the tooth.

To release the pin 14 from the guard the action is reversed by slightly rocking the plastic guard 19 on the spring leg 12 of the pin structure and forcing the leg 11 to and from the channel 20 so as to clear the guard 10.

Thus there is provided a novel guard structure of durable, non-bendable material formed to normally confine and double lock the pin point of a novel pin structure, to thereby provide for greater safety and superior operation than heretofore, said pin point being always biased within the confines of the guard adjacent the partition confined within the walls of the guard for maximum safety.

Without further description it is believed that the present invention is clearly understandable and it is to be expressly understood that other arrangements of parts and combinations thereof may be made by others skilled in the art without departing from the scope of the invention as defined in the appended claim.

I claim:

A safety pin comprising a wire loop and guard with one end of the loop embedded in the guard and the other end being pointed and biased within the confines of the guard, said guard comprising a hollow rectangular body open at the bottom and side thereof and having a top wall, one side wall, opposite end walls, and a partition extending longitudinally of the guard from one end wall in spaced relation to the other end wall in the provision of a slot for receiving the pointed end of said biased leg, said partition being spaced from the side wall and within the confines of the top wall, said side wall and said end walls, so that said top wall and end walls extend laterally of the guard beyond the exterior face of the partition, whereby the leg of the loop having the pointed end is biased to a position under the said top wall to maintain the pointed end of the loop always under cover of the top wall.

CHARLES MILTON CLARK.
